COMPUTING MACHINE

Walter W. Landsiedel, Elmira, N. Y., assignor to
Remington Rand Inc., Buffalo, N. Y., a corporation of Delaware

Original application April 6, 1936, Serial No.
73,020. Divided and this application March 17,
1939, Serial No. 262,351

3 Claims. (Cl. 235—60)

This invention relates generally to adding and listing machines and more particularly to the printing of special characters to identify total, sub-total, and non-add operations of said machines.

This application is a division of application S. N. 73,020, filed April 6, 1936, now Patent No. 2,229,980, issued January 28, 1941. The machine shown and described herein represents an improvement of the adding and listing machine disclosed in the patents to Mehan Nos. 1,835,170, 1,876,719, and 1,899,444.

The object of the present invention is to more conveniently and efficiently cause the printing of a character to identify a total, sub-total, and a non-add operation of the machine.

In carrying out the above object, the total link is provided with a pair of cams arranged in different planes. Means is provided which normally cooperates with one of said cams in such a manner that, when a total is taken, the cam causes the above means to move to a position whereby the character bar is permitted to move to a position to print a total designation. Additional means is provided which is operable upon the depression of a sub-total key. This additional means is adapted, when operated, to move said first mentioned means into cooperative relation with the second of said pair of cams. The relation is such that, when the total link operates upon depression of a sub-total key, the cam moves the first mentioned means to a position whereby the character bar is permitted to move to a position to print a sub-total designation. Also, the additional means is moved into cooperative relation with the second cam upon the depression of the non-add key in the same manner as when the sub-total key is depressed. But, as the total link is locked against movement whenever the non-add key is depressed, the first mentioned means is not actuated by the second cam during the non-add operation of the machine. When the first mentioned means is in its operated position, i. e., when a sub-total or non-add key is depressed, the mechanism is in position to permit the character bar to print a sign to identify a non-add operation of the machine.

While the present invention is herein shown and described in connection with the above type of machines, it will be understood that it can be used with other types of adding and listing machines without departing from the spirit of this invention.

In the accompanying drawings, wherein like

reference characters represent corresponding parts in the various views,

Fig. 1 is a right-hand side elevation of the machine, the case of which is shown in vertical section, and with parts removed or shown in section or broken away;

Fig. 2 is a front to rear vertical section through the machine with some parts omitted, other parts partially broken away and still others shown in elevation;

Fig. 3 is a partial right-hand elevation in section just outside the left inner side frame and showing the parts in normal position;

Fig. 4 is a plan view of Fig. 7, including the left inner side frame;

Figs. 5, 6, 7 are detached diagrammatic views of mechanism concerned in shifting the character shaft to various positions. In Fig. 5 the full lines show the parts in normal position and 20 the dotted lines show the four positions of the character stop operating shaft; in Fig. 6 the total slide is shown in normal position by dotted lines and in the total position by full lines with the character shaft shown in the total position; 25 and in Fig. 7 the total slide is shown as described in Fig. 6 but with the character shaft shown cammed to the sub-total position by said total slide;

Fig. 8 is a fragmentary perspective view of a 30 portion of my improved mechanism; and

Fig. 9 is a fragmentary sectional view illustrating character-printing mechanism.

In the accompanying drawings I have shown only so much of said machine as may be necessary to arrive at an understanding of my present invention in its embodiment therein.

From a consideration of Figs. 1 and 8, it will be seen that the frame of the machine by which the various working parts are supported comprises left and right outer frame plates 100 and 101, respectively, united by cross bars 102 and 103, by the upper keyboard plate 104 and by the base or bed plate 105; also, left and right inner frame plates 281, 282, between which the register and printing mechanisms are mounted.

The computing and printing operations, determined by the set-up of the digit keys 106, are controlled in the present instance by the motor bar 107, Fig. 1, mounted at the right-hand side of the machine and which bar controls the electric motor (not shown) which drives the main rock shaft 109, though obviously said shaft may be hand driven by the usual handle carrying crank shown in Patent No. 1,899,444.

The digit keys 106 and the step-by-step mov-

ing pin carriage 117 are the same as those disclosed in the above mentioned Mehan patents and need not be redescribed here. Pins 118 (Fig. 2) cooperate with lugs 336 on transfer slides 319 to control the differential positioning of actuating racks 119 through the actions of springs 120 and bail 328, which bail is reciprocated by the main shaft 109. Reference may be had to the parent case for a complete description of parts 319 and 119. These parts are also claimed therein.

Motor drive

Referring now to the motor drive and especially to Fig. 1, the small electric motor is secured to the base 105 and drives a ratchet disk 188 (which is an element of a one-revolution clutch), through speed-reduction gearing (not shown). Ratchet 188 is mounted for rotation upon shaft 182. The driven member of said clutch consists of a drive crank or disk 189 carrying a clutch pawl 200 adapted for engagement with and disengagement from the ratchet 188. Said disk carries roller 243 playing in a slot 244 in a two-armed drive lever 245 which in turn carries a stud 248 playing in a radial slot in an arm 251 on the main shaft 109. A spring-pressed clutch pawl 200 is used, when the motor is running to connect the disc 189 and the ratchet 188 so as to drive the main shaft 109. As the motor drive details are not necessary to an understanding of the present invention, it is sufficient to say that engagement and disengagement of the clutch is caused by the rocking of a control lever 210, pivoted on a stud 186. This lever (shown in normal position in Fig. 1), when it is swung counter-clockwise, allows engagement of the clutch and also causes the closure of contacts 238 and 239 to start the motor. The control lever 210 may be tripped by counter-clockwise swinging of a lever 223 which lever moves a link 219 to trip control lever 210. Actuation of lever 223 can be caused either by depressing motor bar 107 or by depressing the non-add key 110 (Fig. 3) or the sub-total key 111, as will be explained in detail later in this specification.

Automatic total mechanism

In the present machine there is no total key, but a total is taken by causing the machine to perform two cycles of operation by depressing the motor bar 107. These two cycles may be made consecutively without stopping the motor by merely holding the motor bar down. The first cycle is the usual blank stroke made in order to clear any transfer devices which may have been tripped in the last preceding adding operation and the second is the total cycle.

In order to distinguish the blank stroke, there is employed the so-called "blank stroke lock," which, together with the balance of the automatic total mechanism, is shown in Fig. 8. The blank stroke lock comprises a bar 370 situated on the right-hand side of the machine, its rear end guided for sliding motion on a stud 371 projecting from the right-hand frame plate 101 and its forward end pivoted to an arm 372 fast on a transverse rock shaft 373 at the front of the machine, just under the keyboard plate. In Fig. 8, the shaft 373 has been broken away and its right-hand end offset so as to keep it within the limits of the drawing. The bar 370 has pivoted thereto a latch 374, controlled by a spring 375 so disposed as not only to rock said latch coun-

ter-clockwise in Fig. 8, but also to urge the bar 370 bodily toward the rear of the machine. Said latch is adapted to engage as shown in Fig. 8 over a flange 376 erected near the rear right-hand corner of the carriage 117, in such position that said latch will engage said flange only when the carriage is in its right-hand position. When one key has been struck and the carriage makes its resulting step, this flange moves leftward out of engagement with the latch and leaves the bar 370 free to move toward the rear of the machine, rocking the shaft 373 clockwise.

In order to restore the bar 370 to its forward position, said bar is made with an offset branch 377 having an inclined rear edge 378 adapted to be acted on in the latter part of the forward stroke of the main shaft 109 by a pin 380 projecting from a piece 251 mounted on said shaft. If a key has been struck the carriage 117 will be at the left of its initial position and the flange 376 will not be engaged by the latch 374, so that on the return stroke of the main shaft the bar 370 will again slide to its rear position. In the case of a blank stroke, however, that is to say, one in which no key has been operated, the bar 370 would move forward as described and will be retained in its forward position, so that at the beginning of the next stroke the shaft 373 will be standing in its normal position.

Near its left-hand end, said shaft 373 has an arm 381 having a stud 382 playing in a vertical slot in an ear 383 formed up from a slide 384, which slide rests on the lower keyboard plate 114. The left end of the shaft 373 is pivoted in an ear 385 formed up from said plate. When the slide 384 is moved toward the rear of the machine in unison with the rearward movement of the bar 370, the upper edge of the ear 383 moves under the right-hand end of and locks against downward movement a lever 386, which is pivoted to a fixed bracket 387 and held up by a spring 388.

From the preceding description, it will be perceived that the ear 383 locks this lever 386 in the first part of every cycle in which a key has been depressed, and also during the first part of the next succeeding cycle even though that may be a blank cycle. This lever is unlocked in the latter part of the forward stroke of the blank cycle.

The lever 386 has near its free end an opening into which projects the horizontal arm of a bell-crank 390 to the depending arm of which is pivoted a link 391, which at its rear end is pivoted to the link plate 392, which is part of the mechanism for throwing the register wheels into and out of mesh. This plate link 392 normally occupies its forward position shown in Fig. 8, in which it sets the machine for addition, but when swung to its rear position by rearward movement of the link 391, it sets the machine for taking a total. From what has been said hereinbefore it will be perceived that the mechanism is locked in adding position during the first part of every adding stroke and of the first blank stroke following an adding stroke; but that during the first stroke following said blank stroke, the ear 383 unlocks the bell-crank 390 leaving the link 391 free to set the machine for total taking.

The bell-crank 390 is one branch of a bail which also comprises a bail bar 393 and a left-hand bail arm 394, said arms being pivoted on a rod 395, which is mounted at one end in the left-hand frame plate 100 and at its inner end

in a bracket or ear 396 formed up from the plate 114. The arm 394 has pivoted to its lower end the front end of the so-called "total slide" 353, which near its rear end has a slot by which it is slidably mounted on a fixed stud 397. This slide is drawn rearward by a spring 398, which furnishes the power to rock the bail 390, 393, 394 and to move the link 391 rearward to set the machine for total taking.

The total slide 353 is normally held in its forward or adding position by an arm 400, constituting part of a cam plate 401 fast on the main shaft 109 between the frame plates 100 and 282, said arm 400 acting on a stud or roll 402 projecting from a rearward extension of the slide 353. In the first part of the forward stroke of each cycle of the machine, the arm 400 moves rearward and the slide 353 will follow it provided it is unlocked at 383—386, which it will be on the second cycle following an adding cycle.

Some of the above mechanism is also shown in Figs. 3 and 4.

As the carriage 117 remains in its right-hand position, not only during the blank stroke but also during the total stroke, the total slide 353 will remain unlocked after a total stroke, so that successive totals may be taken without any intervening blank stroke. In other words, if after a total has been taken the motor bar 107 is again depressed, the mechanism will again go through the movements of taking a total and these will be repeated as often as said motor bar is struck. This would, of course, be an idle operation except in the case of taking sub-totals as will be explained hereinafter.

The cam plate 401 is made with a projecting peripheral flange 403 arranged for cooperation with a roll 404 mounted on a stud projecting from the total slide 353. The construction is such that when said total slide is in its normal position, the flange 403 comes down behind the roll 404 and prevents said roll and the slide 353 from moving rearward unless such movement takes place in the very first part of the cycle. In case the slide does move rearward in the first part of the cycle, the flange 403 comes down in front of the roll 404 and positively holds the slide in its rear position. It will be recalled that the slide 370 is restored to its forward position in the latter part of the forward stroke of each operating cycle, thus unlocking the lever 386. At this time, however, the roll 404 is in engagement with the flange 403 and nothing happens. If, however, at the beginning of the following stroke, the lever 386 is still unlocked then the slide 353 will move rearward and set the machine for total taking as soon as permitted by the arm 400.

The machine is equipped with a non-add key 110 (Figs. 4 and 8) the stem of said key having a sliding motion in the keyboard plates, and a return spring like other keys.

The effective part of this key consists of a formed arm 461 projecting toward the left and including a part that overlies the forward arm of a non-add lever 462, which is pivoted on a stud 463 mounted on a bracket riveted to the underside of the keyboard plate 104. This lever has the shape best shown in Fig. 3. Its rear arm extends at a downward inclination terminating in a concentric edge 465, preceded by a cam curve 466, adapted to act on a pin 467, projecting from a lever 468 pivoted at 470 to a stud projecting from the left-hand frame plate 100.

When the non-add key is depressed, it swings the lever 462 counter-clockwise as viewed in Fig. 3, and the edges 466 and 465 thereof, acting on the pin 467, rock the lever 468 clockwise and hold it in that position. The rear edge of this lever has a curved or camlike shape, shown in Fig. 3, and when it is rocked rearward, this edge is in position to engage a pin 471 (Fig. 8) projecting from the wipe pawl 432 at the time when said wipe pawl is in its lower position, the said edge of the lever 468 holding the wipe pawl disabled during its return stroke so that on the up-stroke of the arm 431 said wipe pawl will not move the register wheels into engagement.

In order to take sub-totals, this machine has the same general mode of operation as other machines of this type, that is to say, by holding the wipe pawl 432 out of engagement with the pin 436 (Fig. 4) at the beginning of the return stroke of the main shaft in a total taking cycle. In other words, the sub-total mechanism consists of a combination of the total-taking mechanism and the non-add mechanism.

The sub-total key 111 (Fig. 4) is mounted in front of the non-add key and has its stem guided in the keyboard similarly to other keys. The stem of this key comprises a branch 472 (Figs. 3, 4, and 8) which overlies the forward end of the lever 462 and acts on it the same as the non-add key; in fact, in this machine, the non-add key could be used for a sub-total key except that it is desirable to provide certain interlocks to guard against confusion and misoperation. It will be recalled that the machine is set for taking a total by the mere act of depressing the motor key 107 twice. If the sub-total key is depressed for the second of these operations, the total will be a sub-total as above described.

The essential element controlled by these two keys is the wipe pawl controlling lever 468. In order to retain this lever in its rear position, during the whole forward and return stroke of the operating shaft, said lever is connected by the pin 467 above mentioned with another lever 490 (Figs. 3 and 4) which lies adjacent the inner face of the cam disk 401 and has a stud or roll 491. An arc-shaped flange or member 492 is secured by rivets to such face of said cam disk. The construction is such that with the parts under consideration standing in normal position, early in the forward stroke of the main shaft, this flange 492 will move down in front of the roll 491 and prevent actuation of the non-add mechanism at any time until the end of the cycle. If, on the other hand, the non-add or sub-total key has been depressed, the roll 491 will occupy a rear position and the flange 492 will move down in front of it and positively retain the parts in proper position until the end of the cycle, notwithstanding the release of the key. The lower end of the flange 492 is beveled at its rear side as shown in Fig. 3 so as positively to complete the motion of the levers 490 and 468 in case that was not done by the key. This locking mechanism makes the action of these control keys largely independent of the retaining of the keys themselves in depressed position.

Means are provided whereby a depression of either the non-add key or the sub-total key will set the operating mechanism into action the same as the motor bar 102. This saves a double operation and it is permissible because these two keys are locked except at times when it is proper to operate them. Both these keys rock the lever 462 and this lever is, therefore, utilized

to trip the motor mechanism. To this end, a finger of said lever is pivoted at 493 (Figs. 3, 4, and 8) to a link 494, whose forward end is pivoted to an arm 495 fast on a transverse rock shaft 496 journaled at its ends in the outer frame plates 100 and 101. At its right-hand end (Fig. 1) said shaft 496 has an arm 497 overlying a roll 221 on the lever 223, which actuates the trip lever 210. By this train of mechanism either of the two keys 110 or 111 will start the motor and cause a cycle of operation.

Improved character control

The character control mechanism which forms the subject matter of the present invention is best illustrated in Figs. 3 to 7, inclusive, and in Figs. 8 and 9. Adjacent the type bar 153 of lowest order there is arranged a character type bar 343 containing special types for printing various characters. In the present instance three such types are shown, one for total, one for non-add and one for sub-total, all normally below the printing line.

The character type bar 343 is guided by combs 263—264, plate 266 and bar 267 in the same manner as the numeral type bars 153. This type bar 343 is moved vertically by a pinion 344, rack bar 345, and slide 346, said rack bar actuated by a spring 120 and by the restoring bar 328, much the same as the numeral rack bars. The slide 346, however, does not have any projection 336 (Fig. 2) for cooperation with pins or stops in the stop carriage 117, but is, on the contrary, controlled by special devices now to be described, said devices cooperating with a special lug 348 secured to the rack 345 and a screw 349 carried by the right center frame plate 281. The rack 345 is guided in the same way as the numeral racks.

Character stop operating shaft 350 is journaled in the center frame plates 281 and 282 and extends outwardly beyond the left plate 282 to receive the operating arm 351 which is pinned thereto as shown in Fig. 4 and also in Fig. 3, which is a section taken just outside of frame 282. The outer free end of this arm carries an outwardly projecting pin 352 (Figs. 4 and 9) which is acted upon by total slide 353 in a manner presently described.

Just inside of the right center frame plate 281 and secured to the shaft 350 is a gear segment 354 the teeth of which are in permanent mesh with teeth 356 on the character stop 357. This character stop is best illustrated in Figs. 8 and 9, and pivots upon a shaft 413, and is provided with three steps designated 359, 360, and 361 of progressively greater distances from the shaft. During certain operations of the machine one or another of these steps serves to arrest the special lug 348 and hence the rearward movement of rack 345. The stop 357 (or character fan as it is sometimes termed) is shown in normal position in Figs. 8 and 9 and during an adding operation the lug 348 engages the closest or lowermost step 359 which prevents the rack 345 from being moved rearwardly by its spring 120 enough to cause the character type bar 343 to rise to any printing position.

During a total taking operation the total slide 353 is permitted to be drawn rearwardly by its spring 398 which moves the cam surface 363 of said slide underneath the pin 352 (Fig. 6) to elevate the pin from edge 364 to edge 365 of the total slide. By a study of Fig. 9 it will be understood that when the pin 352 is elevated as just described, the free end of the arm 351 is likewise

elevated which in turn rotates the shaft 350 counter-clockwise. This movement of the shaft rotates the gear segment 354 counter-clockwise and the character stop 357 clockwise to bring step 360 into the path of lug 348. This permits the rack 345 to move rearwardly one unit which raises the type bar 343 one unit to bring the character type 366 to position to print a star, indicative of a total.

In order to cause the second type on the type bar 343 to print a sign to indicate non-add, the piece 468 (Fig. 3) which is swung clockwise by depression of said key has a pin 516 playing in a slot in a link 517 which is pivoted to the pin 352 above mentioned. Said pin 352 is connected with the pin 516 by a tension spring 518. The parts are so proportioned that an actuation of the piece 468 rocks the shaft 350 to the third position from the bottom indicated in Fig. 5, which, in turn, rocks the stop piece 357 to bring the step 361 thereon into the path of the lug 348.

It will be recalled that this piece 468 is also actuated by the sub-total key, but that, when the latter is operated, the total slide 353 moves toward the rear of the machine. Said total slide is, therefore, made with a tooth 420 with an inclined end. When the pin 352 is raised to the non-add position, it stands just back of the inclined rear end of this tooth so that when in response to an operation of the sub-total key the slide 353 moves rearward, this inclined end cams the pin 352 to its uppermost position in Fig. 5 with the result that the stop piece 357 is rocked so far down that the lug 348 passes over the top of it and is not arrested by it. In this operation, the upward motion of the type bar 343 is arrested by a screw 349 (Fig. 9) passing through a slot in said type bar, said slot being of a length suitable for the purpose.

The hammer 272 for the character type bar is actuated the same as the other hammers. Whether or not this particular hammer makes its stroke depends entirely on whether the special rack bar 345 has been moved from normal position. Therefore, in case of a total or sub-total operation when the register is clear, the appropriate designation will be printed, though no number will be printed.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In an adding and listing machine, the combination with registering mechanism, numeral printing mechanism, total taking control mechanism and control keys including a sub-total key for modifying the operation of the machine, of means for printing characters designating different operations, said means comprising a character type carrier, a stepped stop member for controlling differential settings of said type carrier, a cam moving with said total taking control mechanism, operable means under control of said cam to move said member to a point to cause said type carrier to be arrested in position to print a total designation, a second cam moving with said total taking control mechanism, and means actuated upon depression of said sub-total key to

move said operable means out of cooperative relation with said first cam and into cooperative relation with said second cam whereby said member is moved to a point to cause the arrestment of said type carrier in position to print a sub-total designation.

2. In an adding and listing machine, the combination with registering mechanism, numeral printing mechanism, total taking control mechanism, and non-add control mechanism, of means for printing characters designating different operations of the machine, said means including a differentially settable type carrier, a stepped stop member for arresting said type carrier in different positions, two cams moving with said total taking control mechanism and one situated above the other, a follower operatively connected with said stepped stop member and adapted to be moved by the lower of said cams so as to set said member to arrest said type carrier in position to print a total designation, means controlled by said non-add control mechanism to set said stepped member and said follower in a second position for printing a non-add designation, a sub-total key for actuating said stepped member and follower to said second position, whereby the upper one of said cams, moving with the total taking control mechanism following depression of the sub-total key acts to move said follower and stepped stop member from non-add position to a

third position to cause the printing of a sub-total designation.

3. In an adding and listing machine, the combination with registering mechanism, numeral printing mechanism including numeral type carriers, total taking control mechanism, and control keys for modifying the operation of the machine including a non-add key and a sub-total key, of means for printing characters designating different machine operations, said means comprising a character type carrier, a stepped stop member for controlling differential settings of said type carrier, a cam moving with said total taking control mechanism and arranged to actuate said stepped stop member to a point to arrest said type carrier in position to print a total designation, a second cam moving with said total taking control mechanism and arranged to actuate said stepped member upon preliminary positioning thereof to a point to permit the arrestment of said type carrier in position to print a sub-total designation, and means operable by said sub-total key and said non-add key for effecting preliminary positioning of said stepped stop member in cooperative relation with said second cam at which point said member is effective to arrest said type carrier in position to print a non-add designation.

WALTER W. LANDSIEDEL.
